GUSTAV BECKERS, OF CREFELD, AND FRITZ LE HANNE, OF BENRATH, NEAR DUSSELDORF, GERMANY.

REED FOR LOOMS.

Application filed January 27, 1915, Serial No. 4,752. Renewed April 24, 1920. Serial No. 376,431.

To all whom it may concern:

Be it known that we, GUSTAV BECKERS, a subject of the King of Prussia, residing at Crefeld, Germany, and FRITZ LE HANNE, a subject of the King of Prussia, residing at Benrath, near Dusseldorf, Germany, have invented a new and useful Reed for Looms, of which the following is a specification.

The invention relates to improvements in reeds for looms of the type which include two sets of dents, all of which are operative on the weft during the "beating up" movement of the lay beam, but one set of which is separated from the other during the picking and shedding operation. By such an arrangement the warp is relieved of a certain amount of wear which would result if all of the dents that are operative in the "beating up" motion were moved thereover to the same extent during the shedding operation.

Specifically the present invention is an improvement upon the reed, of the same general type, heretofore invented by us and disclosed in British Patent No. 28,623 of 1913.

According to the present invention the movable dents of the reed are of S-shape, that is have their ends curved in opposite directions and extend across the plane of the fixed dents. The ends of the several movable dents are connected by suitable bars so that while they are free to move in the spaces between the fixed dents, the two sets of dents are permanently interlocked.

The accompanying drawing illustrates a preferred form of reed construction in accordance with the invention. In said drawing:

Figure 1 is a front elevation;

Figure 2 is a vertical section, showing the several parts in the positions occupied while forming the shed, the slay sole and cap being also illustrated;

Figure 3 is a vertical section showing the positions of the several elements of the reed during the "beating up" movement;

Figure 4 is a transverse section on the line A—B of Figure 1.

Referring to the drawing the reed comprises a set of straight, relatively fixed, or stationary, dents *a* and a series of auxiliary, movable, curved dents *b*. The fixed dents *a* are, as usual, fastened to bars *F* which are arranged in a frame including top and bottom strips *E* and end strips *c*. The

auxiliary, or relatively movable, dents *b* are similarly connected with a frame comprising bars *V*, strips *n* and end members *d*. The latter members are provided with blocks *f*, of the cross sectional form shown in Figure 4, which extend over the rear faces of the end strips *c* of the fixed dent frame. The connection between the blocks *f* and frame members *d* is indicated at *g* in Figure 4.

The lower strip *n* of the frame of the auxiliary, movable, curved dents *b* rests on brackets extending rearward from the lower frame strip *E* and terminating in upwardly extending flanges *r*.

Projections or studs *h* on the end strips *c* extend through slots *H* in the projections *f'* of the blocks *f* in rear of said strips and assist in supporting the dents *b* as well as to guide them during the separation that occurs in the shedding movement. The extent of separation of the two series of dents, is limited by contact of the projections *f'* on the blocks *f* with the end strips *c* of the frame of the fixed dents.

Screw bolts *k* extend rearward from the side strips *c* of the frame of the fixed dents, through the flange *f'* of the blocks *f* and about said bolts, between nuts *m* thereon and the flange *f''*, are arranged coiled springs *l*. It will be seen that by the relative movement between the two series of dents during the "beating up" operation the springs *l* will be slightly compressed and will assist in separating the auxiliary dents from the fixed dents as the beam moves in the shedding operation.

While the reed is moving in the direction of the arrow *P'* (Fig. 2) during the formation of the shed, the frame carrying the fixed, straight, dents *a* is positively moved by the loom beam but the movable dents are restrained from such movement by the rubbing action of the warp threads thereon, which restraining action tends to separate the two sets of dents as illustrated in Figure 2. This separation is initially assisted by the action of the springs *l*.

This separation of the two series of dents permits the complete reed to move quite freely during the shedding operation and provides spaces of maximum width between the several dents, thus affording free passage for the warp threads, knots and thick-

ened parts thereof, so that danger of damage to the threads during the shedding operation is prevented.

During the shedding operation therefore the two series of dents will be separated, or the portions of the movable auxiliary, dents engaged by the warp drawn out of the spaces between the fixed straight dents and the flanges *r* on the brackets attached to the lower strip *E* of the frame of the fixed dents moved away from contact with the strip *n* connecting the lower, rearward, ends of the movable dents, as shown in Figure 2.

When the beam moves forward in the direction of arrow *P²* (Figure 3) during the "beating up" operation, the frame of the straight dents, and said dents, will be first carried forward substantially alone or more rapidly than the movable dents until the bodies of the movable dents are again in the spaces between the fixed dents and the flanges *r* contact with the strips *n*. Thereafter the two sets of dents move together so that all of the dents are caused to act upon 25 the weft and effect a close weave.

While portions of the curved dents are always extending through the spaces between the straight dents and the two series can not be entirely disconnected, it will be seen that the warp engaging portions of the two series will be automatically separated during the shedding operation while all of them will be operative during the "beating up."

Having thus described the invention what is claimed is:

1. A reed for looms comprising a series of relatively straight dents, a second series of dents adapted to move transversely through the spaces between the straight dents and having their ends curved in oppo-

site directions, and means for guiding the curved dents in their movement relative to the straight dents.

2. A reed for looms comprising a series of relatively straight dents, a frame therefor, a second series of dents having their ends extending in opposite directions through the spaces between the straight dents, means to cause said dents to automatically pass out 45 of the spaces between the straight dents during backward movement of the lay, and means for supporting and guiding said second series of dents whereby they may re-enter said spaces during beating up movement of the reed.

3. In a reed for looms, in combination, a framed set of straight dents and a framed set of dents curved to S-shape, said curved dents passing through the interstices between the straight dents.

4. In a reed for looms, in combination, a framed set of straight dents, another framed set of dents curved to S-shape, said curved set of dents being adapted to move across 65 the set of straight dents and guides fixed to the frame of the movable set of dents above its center of gravity.

5. In a reed for looms, in combination, a framed set of straight dents, another framed set of S-shaped dents, the S-shaped dents being adapted to move across the plane of the straight dents and stops at the frame of the straight dents limiting said motion of the curved dents.

In witness whereof we have hereunto set our hands in the presence of two witnesses.

GUSTAV BECKERS.
FRITZ LE HANNE.
